WITNESS:

Rene' P. Quinn

INVENTOR:

Henry P. Kraft,
By Attorneys,
Fraser, Funk & Myers

UNITED STATES PATENT OFFICE.

HENRY P. KRAFT, OF RIDGEWOOD, NEW JERSEY, ASSIGNOR TO A. SCHRAEDER'S SON, INCORPORATED, OF BROOKLYN, NEW YORK, A CORPORATION OF NEW YORK.

ETHYL-CHLORIDE TUBE.

Application filed January 2, 1919. Serial No. 269,271.

To all whom it may concern:

Be it known that I, HENRY P. KRAFT, a citizen of the United States of America, residing in Ridgewood, in the county of Bergen and State of New Jersey, have invented certain new and useful Improvements in Ethyl-Chloride Tubes, of which the following is a specification.

This invention relates particularly to tubes for containing ethyl chloride or other highly volatile liquids which are expelled from the tube by the internal pressure due to the heat of the hand, although it is applicable to other purposes.

15 The ejection nozzle for such tubes is usually in the form of a fine capillary opening, commonly formed in the neck of the tube itself. It has heretofore been proposed to form this nozzle of a separate piece of glass and to hold it in place by a sleeve which is in engagement with the neck of the tube. Such nozzles are not accurately formed as to length and it is desirable that there shall be a capacity for adjustment in the sleeve 25 to take up such variations. The device is usually provided with a stopper hinged to one side of the sleeve, and provided with a thumb-piece or handle by which it is adapted to be pressed away from the top of the capillary opening, being returned to closing position by a spring.

30 According to the present invention, I provide a structure of this type which is capable of being positioned on the neck of a tube which has an outwardly extending flange or bead, and according to the preferred form of the invention I provide a construction which includes a portion bearing against the underside of the neck bead, whereby a fixed connection is secured which holds all of the parts firmly in place. The invention includes certain other features of improvement which will be hereinafter more fully described.

45 Referring to the drawings which show several forms of the invention

Figure 1 is an elevation of the upper part of a tube showing the device in place;

Fig. 2 is a similar view, at right angles to Fig. 1, showing certain of the parts in section;

Fig. 3 is an elevation of the sleeve of Figs. 1 and 2.

Fig. 4 is a cross-section of Fig. 3 on the line 4—4;

Fig. 5 is an elevation of the collar detached; and

Fig. 6 is a view similar to Fig. 2, showing a modified construction.

Referring first to Figs. 1 to 5, let A indicate an ethyl chloride tube having a neck B. Such necks are usually formed with an outwardly extending flange or bead C.

Resting upon the flange is a capillary nozzle D, usually formed of glass and provided with a fine hole E. Between the capillary nozzle and the top of the neck is arranged a packing ring F which makes a tight joint between the nozzle and the neck.

In one form of the invention I provide a sleeve G, which is of sufficiently large diameter to slip down over the neck past the bead C. My invention provides means for holding the sleeve G fixedly in place against any outward strain. In the construction of Figs. 1 to 5, I form a plurality of holes in the sleeve and in each hole insert a compressible member, such as H, which is adapted to extend through the sleeve to a sufficient extent to engage the underside of the bead F. To press such compressible members inwardly and to hold them in place, I preferably provide a collar J which is internally screw-threaded to engage the lower screw-thread K of the sleeve G. Preferably the upper end of the collar is slightly flared so that it may easily pass the lower edges of the compressible members H. By screwing up the cap, these members are pressed inwardly, thus clamping the sleeve G fixedly in place on the neck.

The sleeve G is also provided with an upper thread L, upon which screws a cap member M which has an internal flange N, adapted to engage the upper end of the capillary member D. By screwing down the cap, the capillary member is hence forced downwardly against the packing F until a tight joint is obtained. This construction permits the use of widely different lengths of capillary members with equal efficiency. The stopper O is best formed as a lever

pivoted at P to the cap member M and carries a rubber pad or facing Q at its upper end, which is adapted to be pressed against the top of the capillary opening by a spring 5 R, reacting against the lower end S of the lever. The latter serves as a handle or thumb-piece by which the stopper can be displaced from over the top of the capillary opening.

10 In the construction shown in Fig. 6, the collar J and compressible members H are omitted, and the sleeve G' is held in fixed position by a spring T. The spring being of elastic construction is capable of sufficient 15 expansion to pass over the bead of the neck and the sleeve is formed internally at its lower part with a helical recess or thread designed to receive the upper part of the spring. When the spring is so inserted in 20 the sleeve, it, of course, cannot expand to pass upwardly over the bead. It hence forms a fixed stop which prevents the upward movement of the sleeve. Preferably, the cap M' screws on the top of the sleeve as before, 25 whereby the packing ring may be compressed and different lengths of capillary members accommodated. Such adjustments can also be made by screwing the sleeve upon the spring to a greater or less extent, in which 30 case the cap M' can be formed in one piece with the sleeve G'. The compression of the packing ring however, requires the application of some little force, and during the screwing movement of the sleeve the spring would 35 necessarily have to be held against rotation with the result that, in the hands of a careless workman, possible distortion of the spring would take place. I therefore prefer to 40 adjust the spring fully in place so that it forms a more or less rigid stop, and to provide the threaded cap for forcing down the capillary member against the packing. During 45 this operation the more rigid sleeve can be grasped, and the spring is subjected only to a compression strain. If desired, the spring may be continued downwardly until it encloses the entire neck and a few convolutions, such as those shown at T', may be flared outwardly so as to lie on top 50 of the tube body, thereby not only forming a protection for the neck itself, but also for the juncture of the neck with the tube. This guards the parts from liability of 55 breakage, if the neck or stopper is carelessly subjected to any exterior shock.

While I have shown and described several forms of the invention, it will be understood that I do not wish to be limited thereto, since various changes may be made therein without departing from the spirit of the invention.

What I claim is:

1. The combination of a vessel having a neck, a removable sleeve fitting onto said neck, removable means engaging said neck

65 to prevent outward movement of said sleeve, a capillary member, a cap engaging the outer end of said member, and a stopper carried by said cap.

2. The combination of a vessel having an outwardly beaded neck, a removable sleeve fitting over said bead onto said neck, removable means engaging said bead to prevent outward movement of said sleeve, a capillary member, a cap carried by said sleeve and engaging the outer end of said member, and a stopper carried by said cap.

3. The combination of a vessel having a beaded neck, a sleeve fitting over said bead, means underlying said bead to prevent escape of the sleeve, a capillary member above said bead, a packing between said capillary member and said neck, a cap engaging the outer end of said member, said parts being adjustable to compress the packing.

4. The combination with a vessel having a beaded neck, of a sleeve fitting over said bead, means for fixedly positioning said sleeve, a screw-threaded cap engaging said sleeve, a capillary member within said cap, the cap engaging the upper end of said member, a packing between said capillary member and said neck, said cap being adjustable on said sleeve to accommodate different sizes of capillary members and to compress said packing, and a stopper carried by said cap.

5. The combination of a vessel having a beaded neck, a sleeve fitting over said neck, a spring surrounding said neck beneath said bead and engaging said sleeve, and a stopper carried by said sleeve.

6. An ethyl chloride tube or the like having a neck, a stopper and means for holding the stopper on said neck, and a protecting member encircling said neck and removably mounted thereon.

7. An ethyl chloride tube or the like having a neck, a stopper and means for holding the stopper on said neck, a protecting member encircling said neck and removably mounted thereon and extending over the point of juncture of said neck with said tube.

8. An ethyl chloride tube or the like having a neck and a protecting member encircling said neck, said protecting member comprising a spring.

9. The combination of an ethyl chloride tube or the like having a neck, a sleeve passing over said neck, a spring constituting a stop for said sleeve, said spring extending downwardly over the neck, and a stopper carried by said sleeve.

10. The combination of a vessel having a neck, a stopper-holding device connected to said neck, a cap screwing on said stopper-holding device and carrying a stopper, and a capillary tube within said cap, the cap engaging the outer end of the tube.

11. The combination of a vessel having a neck, a sleeve on said neck, means for holding said sleeve on said neck in various adjustable positions, and a cap adjustable on said sleeve and adapted to engage a capillary member.

12. The combination of a vessel having a neck, a sleeve on said neck, means for hold-

ing said sleeve on said neck in adjustable positions, a cap adjustable on said sleeve and adapted to engage a capillary member, and a stopper pivoted to said cap.

In witness whereof, I have hereunto signed my name.

HENRY P. KRAFT.
